ELECTRONIC ANALYZER

J. Howard Parsons, Los Alamos, N. Mex., assignor to the United States of America as represented by the United States Atomic Energy Commission

Application March 17, 1949, Serial No. 81,989

3 Claims. (Cl. 177—311)

1

My invention relates to electronic analyzers and more particularly to a system for electronically classifying, cataloging and accounting of the magnitude distribution of a series of events, and is related to the invention disclosed in my co-pending application Serial No. 53,794.

In the physical sciences it is often necessary to determine the magnitude distribution of a series of events. Each event in a series of physical events will occur with a magnitude that is controlled by the operating physical laws. A physical event can be defined as the occurrence of any phenomenon, and the magnitude of the event as a quantitative measure of a variable such as size, brightness, or duration. A series of events is characterized in part by the number of events in each increment of magnitude throughout the spectrum of magnitudes and this distribution is the magnitude distribution. The physical laws that control a series of events can be studied under certain conditions if the magnitude distribution is known. For example, the laws governing grain size in a photographic film may be studied if the distribution of grain size produced under varying conditions can be obtained. The magnitude distribution of a series of events may be obtained by classifying each event as to size, and cataloging and counting the number of events in each increment of magnitude. Such a determination, if performed manually, will be slow and will have a low probability of being a true representation of the magnitude distribution of the series of events, because determinations are statistical in nature and involve large numbers of events, each of which must be operated upon by the observer. The observer can only classify an event within a finite increment of magnitude; therefore, the determination is only approximate. Since manual determination is slow and inaccurate and since there are series of events in which the events occur too rapidly for manual operation, automatic systems are required.

Electronic systems of classifying, cataloging, and counting have been developed that will operate on events occurring at a very high rate. Distribution studies may be made on any series of events by electronic means if the magnitude of each event can be translated into a proportional voltage pulse. The method of translation will depend on the type of event under observation, but a photoelectric scanning system might be a common one. In addition to this translator, the systems involve a discriminator that will distinguish between true observations and interfering effects, a classifier that will measure the rep-

2

resentative pulse voltage, and a cataloger and counter that will record the data in tabular or graphical form.

Systems for providing information of the above character have particular usefulness in the field of measurement of energy releases during nuclear changes, such as the distribution of kinetic energies of alpha particles released by the nuclei of certain radioactive isotopes. In one specific application, the energies of the alpha particles were translated into proportional voltage pulses in an ion chamber. Heretofore, the sample was placed in an ionization chamber and alpha particles emitted therefrom served to ionize the gas within the chamber. A voltage change proportional to the energy of the alpha particle was produced on a collecting electrode as a result of the ionization of the gas and the collection of the ions or electrons. This voltage change was amplified and measured, and served as an indication of the magnitude distribution of the alpha particles, and for the purpose, various forms of systems having different degrees of response and accuracy were employed. However, if electronic systems of classifying, cataloging and counting are to realize their full usefulness, they must operate on events at a high rate, and the results of these operations must reveal fine detail of magnitude distribution. If fine detail is to be retained, either the increment of classification must be very small, or the increment of classification must continuously vary its observational point. While the system of my copending application, supra, generally meets these requirements, it will be apparent that such system does not classify, catalog and count each and every event in a series, but operates on a representative group. That system is, therefore, not useful for all types of magnitude distribution studies, especially where a number of selected events are not representative of the series, where the events do not repeat in some fashion, or where the total number of events is small, necessitating the classification, cataloging and counting of each and every event.

Applicant with a knowledge of the problems of the prior art has for an object of his invention the provision of a system which will act upon each and every event of a series to determine the magnitude distribution of events.

Applicant has as another object of his invention the provision of a system for classifying the events of a series to determine magnitude distribution by converting the events into propor-

tional voltage pulses and translating these voltage pulses into linear positions of a beam of a cathode ray tube.

Applicant has as a further object of his invention the provision of a system for classifying the events of a series by converting them into proportional voltage pulses, translating the pulses into linear positions of the beam of a cathode ray tube, and recording the beam positions with a photographic film or plate to reproduce the displacement distribution which is an exact representation of the original magnitude distribution with all fine details preserved.

Applicant has as a still further object of his invention the provision of a system for classifying the events of a series by converting the events into voltage pulses and translating pulse voltage into a proportional time interval.

Applicant has as a still further object of his invention the provision of a system for classifying the events of a series wherein linear driving amplifiers for the cathode ray tube indicator are eliminated.

Other objects and advantages of my invention will appear from the following specification and accompanying drawings, and the novel features thereof will be particularly pointed out in the annexed claims.

In the drawings, Fig. 1 is a schematic of an arrangement for classifying, cataloging and recording events. Fig. 2 is a graph of a microdensitometer recording of magnitude distribution. Fig. 3 is a schematic of a displacement analyzer form of system for determining magnitude distribution. Fig. 4 is a schematic of one form of integrating circuit and restorer suitable for incorporation into my improved system. Fig. 5 is a series of graphs of voltages plotted against time at a plurality of points in the displacement analyzer form of my improved system. Fig. 6 is a schematic of the synchronous analyzer form of system for determining magnitude distribution. Fig. 7 is a graph showing a plurality of curves of voltages plotted against time at a series of points in the synchronous analyzer form of my improved system. Fig. 8 is a photographic record of a plan view of a cathode ray tube screen showing a series of lines which represent magnitude distribution of events as recorded by the second form of my improved system. Fig. 9 is a detail of a suitable form of voltage comparator and a fragmental showing of a portion of a restorer circuit which may be incorporated in the synchronous form of my improved system. Fig. 10 is a schematic of a form of L. C. circuit suitable for incorporation into the synchronous form or type of my improved system.

Referring to the drawings in detail, and particularly to Fig. 1, a suitable translator, for observing an event 1 and translating the observation into an electronic pulse, such as a photoelectric tube, an ion chamber, or the like, is diagrammatically indicated at 2. It feeds into a classifier 3 and then to the cathode ray tube 4. Lines produced on the screen 5 of the cathode ray tube 4 are projected through the lens 6 of a suitable camera upon a film 7. While the details of the circuits of the different forms of the preferred system will be described at length hereinafter, this diagrammatic illustration will serve to clarify the general procedure employed, and provide a reasonable understanding of the arrangement of elements in a system necessary to accomplish the desired results.

Events as indicated diagrammatically by the

wave form 1 are observed by translator 2 and are converted to representative voltage pulses. They are passed through the classifier 3 to the horizontal deflecting plates of a cathode ray tube 4 where they are utilized to position the beam of the cathode ray tube, and form traces on the screen 5, whose displacement from the reference position is determined by the magnitude of the event as a function of pulse or signal magnitude. Each pulse size acts to cause a bright line to be drawn on the screen with displacement corresponding to signal magnitude. Cataloging is accomplished by photographing the series of resulting positions of the beam on the screen 5. This is carried out by the camera 6 and a photographic plate or film 7 on which is produced a catalog of beam positions having a displacement distribution that is an exact representation of the original magnitude distribution with all fine detail preserved. Counting is accomplished by means of a recording microdensitometer (not shown). This instrument will plot distribution of beam positions and hence the magnitude distribution. A graph or densitometer tracing of such magnitude distribution will be found in Fig. 2.

In the displacement analyzer form of system disclosed in Fig. 3, input derived from any event observation pick up, such as an ion chamber and/or conventional amplifier generally designated as translator 2', is fed into a pulse integrator 8, to be described more in detail hereinafter. The integrator 8 feeds into the horizontal deflecting plates of cathode ray tube 4 and is controlled by the restorer 9, described more in detail hereinafter. The input also feeds through delay line or circuit 10, of known or conventional form. The delay network functions to withhold the trace from the cathode ray tube screen until the output of pulse integrator 8 has reached its peak value. The delayed output signal is impressed upon a univibrator 11 of any suitable type such as that disclosed in my prior copending application, supra, adapted to apply an energizing potential to the intensity grid of the cathode ray tube 4, for a period depending upon the time constants of the circuits thereof, before returning to its stable condition. The univibrator output is also coupled to a network which includes condenser 12, and resistors 13, 14. This latter network is connected at the juncture of condenser 12 and resistors 13, 14 to one of the vertical deflecting plates of the cathode ray tube 4. In this way the condenser 12, which is connected to one vertical deflecting plate of the cathode ray tube 4, is charged up through resistance 14, while resistance 13 serves to leak off the charge from condenser 12 to ground.

Consider the operation of the system for a single pulse and follow the results thereof at the various elements of the system as indicated in the graph of Fig. 5 drawn to correspond to positions on the cathode ray tube screen. The pulse is applied through the input at A to the pulse integrator 8. The shape of the applied pulse is generally indicated by curve A in the graph of Fig. 5. The output voltage of the pulse integrator 8 will follow the rise of the input pulse until such pulse has reached its maximum voltage, as is indicated by curve B of Fig. 5. This output voltage, which, as will be shown, determines the horizontal position or displacement of the trace on the screen of tube 4, will then remain constant until some restoring action takes place. The intensity grid of the cathode ray tube 4 is nega-

tively biased to the point of beam cutoff by a suitable biasing potential (not shown) so that the screen will be dark until some signal or applied potential overcomes this bias. The original pulse is also applied at point A to the time delay line or network 10. The delayed pulse appears at M and is applied to the univibrator 11. The position and shape of this pulse in relation to the voltage magnitudes at points A and B is disclosed by curve M in Fig. 5. At point M it serves to trigger the univibrator 11 which then supplies a square wave in its output D to overcome the bias on the intensity grid of the cathode ray tube 4 and to permit the beam to impinge on the screen. Its position with respect to the other curves and its shape is shown at D in Fig. 5. This square wave is also impressed through resistor 14 upon condenser 12 at E and is transmitted to the corresponding vertical deflecting plate of the cathode ray tube, causing the voltage to gradually build up on the condenser and said plate so that the beam may be deflected vertically to produce a bright vertical line on the screen of the cathode ray tube. Resistor 13 leaks the charge of the condenser 12 to ground to restore this condenser to the "no signal" condition. A graph of the build up of voltage across the vertical plates of the cathode ray tube is indicated by curve E of Fig. 5. When the univibrator 11 returns to its stable condition the potential impressed by it upon the intensity grid of the cathode ray tube 4 is removed so that the beam is no longer permitted to impinge upon the screen. At this point the restorer 9, to be described more in detail hereinafter, is rendered operative to produce a delayed pulse of substantially rectangular form, indicated by curve F of Fig. 5, for rendering pulse integrator 8 inoperative. Thus the result of this operation is that one bright line appears on the screen of the cathode ray tube for each pulse received at A, and the position or horizontal displacement of the line is determined by the pulse voltage.

Referring now to Fig. 4 for a showing of the pulse integrator and restorer circuits, the univibrator 11 delivers a square or rectangular positive pulse to the restorer circuit 9 enclosed in dotted lines. The pulse is differentiated by the R-C network 15, 16 and the positive peak is clipped through the action of the resistor 17 and the tube 18, which may be a triode or any other suitable electric discharge device. The action of the differentiated, clipped pulses on tube 18, through the above network, is to produce a small negative and a large positive wave of substantially rectangular configuration. The output of tube 18 is coupled through blocking condenser 20 to the control grid of a suitable restorer tube 19, which may be of triode construction. Tube 19 is normally negatively biased to cutoff from E. M. F. source 21 which is coupled to the control grid of the tube 19 through resistor 22. It receives its anode potential from the high potential side of condenser 29. The rectangular positive pulses from the tube 18 tend to render tube 19 operative for the purpose indicated hereinafter.

In the pulse integrator 8, the input circuit is coupled through a blocking condenser 23 to a pick up circuit such as an ion chamber and amplifier, as disclosed in my copending application, supra. This input circuit feeds through a diode 24 to the control grid of a cathode follower 25, which is shown as a triode, but which may take any suitable form. The forward or positive side

of diode 24 is grounded through resistor 26. The cathode follower 25 is biased to substantially the point of cutoff by cathode resistor 27, and a resistor 28 is interposed between the upper extremities of cathode resistor 27 and condenser 29, to maintain the potential thereof during the time condenser 29 is charged.

In operation the positive pulses above a predetermined magnitude at point A pass through diode 24 to charge the condenser 29 and raise the potential of control grid of cathode follower 25. This causes an increase in the conduction of the tube and raises the potential across resistor 27. However, after the passage of the pulse, the charge would tend to leak off of condenser 29 through diode 24 and resistor 26 to ground. After a time this would normally tend to lower the grid potential permitting the tube to return to a substantially non-conductive state. To prevent the return of the tube 25 to such a state, the resistor 28 serves, when the tube is rendered operative, to supply a current to condenser 29, so that the charge leaking off of that condenser through resistor 26 is just balanced by the charge reaching it from the cathode circuit of tube 25 through resistor 28. This has the effect of maintaining the operative condition of tube 25 which was initiated by the positive pulse on the control grid of that tube. To restore the tube 25 to a substantially non-conducting condition, the univibrator 11, acting in response to the initial pulse from point A impressed thereon after passing through delay network 10, supplies a square wave to the restorer circuit 9, which pulse is differentiated by condenser 15 and resistor 16 into positive and negative pulses, the positive pulse being clipped by the tube 18 and the resistor 17 so that a small negative and a large positive wave of substantially rectangular shape results at condenser 20. The positive wave serves to trigger tube 19, causing it to conduct, and providing a low impedance path to ground for discharging condenser 29. Discharge of condenser 29 lowers the potential of the control grid of tube 25 and permits said tube to return to the substantially non-conducting state. This has the effect, as heretofore indicated, by curve B in Fig. 5, of causing the voltage output of the pulse integrator to rise with the input pulse and thereafter to retain its magnitude over a predetermined period until abruptly lowered by the action of the restorer 9 in response to the collapse of the square wave from the univibrator 11.

The modification of my improved system disclosed in Fig. 6 does not directly utilize the original pulse to determine the beam position, as in the displacement analyzer form of system set forth in Fig. 3, but first translates the pulse voltage into a proportional time interval. This offers some additional advantage, since it avoids the necessity for linear driving amplifiers for the cathode ray tube. Further a smaller tube can be utilized due to the provision for a circular sweep.

In this system, the original pulse at A' from the pick up device and amplifier or other form of translator 27, is applied to a pulse integrator 30 which may be similar to that heretofore described in connection with Fig. 4, or may take any other suitable form. The peak voltage produced at point Z, the output of the integrator, may be maintained at or near maximum magnitude. The output of the integrator 30 is impressed upon a voltage comparator 31, preferably consisting of

biased diodes and a univibrator, to be described more in detail hereinafter. The original pulse at A' is also delayed by any suitable known or conventional delay circuit 32 and the delayed pulse is then simultaneously applied at point Y to a saw-tooth generator 33 and a univibrator 34. The saw-tooth generator may be of conventional type such as disclosed in Hoag on Basic Radio, published in 1942 by D. Van Nostrand Co., Inc., New York, N. Y., pages 165, 168 and 234, or used generally in radar systems, or may be of any known type which is suitable for the purpose. Also the univibrator may be of any suitable known type, but is preferably of the type disclosed in my copending application, supra. This delayed pulse serves to actuate univibrator 34 and saw-tooth generator 33 after the output of the pulse integrator 30 has reached its maximum value. The saw-tooth generator 33 is coupled to the biasing circuit of the comparator 31, and serves to render it operative. A univibrator in the comparator 31 will trip when the voltage of the saw-tooth from the generator 33 is equal to or overcomes the biasing voltage of the integrator 30 at point Z. The time required for the saw-tooth voltage to go from zero to the voltage produced by the integrator will be proportional to the magnitude of the voltage on the integrator which corresponds to the peak voltage of the pulse. Therefore, a measure of this time will be a measure of peak voltage of the original pulse.

The univibrator 34 commenced operation in response to the same pulse at point Y that rendered the saw-tooth generator 33 operative. The generated square wave of univibrator 34 is impressed upon an L. C. circuit 35, to be described more in detail hereinafter, and the resulting out of phase voltages cause the beam of a cathode ray tube 36 to sweep in a circular fashion. When the univibrator in the comparator 31 is actuated by the saw-tooth wave, the intensity grid of the cathode ray tube 36 acts to intensity the beam. The comparator also feeds into restorer circuit 37, described hereinafter in connection with Figs. 9 and 10, for closing circuits about components of the L. C. circuit 35 and reducing their potentials substantially to zero for de-energizing them. This has the effect of producing a bright radial line 38 on the screen of the tube 36. The angular position of this line is a measure of the proportional time. In addition, the restorer 37 acts upon the collapse of the square wave signal from comparator 31 to remove the peak output voltage from the output of the integrator 30 and restore it to normal inoperative condition. The other circuits are also restored to normal condition and the cycle repeats with each subsequent pulse.

Thus the angle and/or position of the radial line on the scope or screen is a measure of peak voltage of the pulse. A photograph of a series of these radial lines as indicated in Fig. 8, will be a catalog of the original series of pulses. The angular distribution of these lines will be the same as the original magnitude distribution of the events with all fine details preserved. A modification of this system could employ the saw-tooth voltage to sweep the beam. This, however, would result in a linear catalog which could not effectively utilize tube size. Another modification might employ a spiral catalog which would tend to improve tube screen utility, and could be realized by replacing the L. C. circuit 35 with an R. L. C. circuit.

Referring now to Fig. 9 which discloses a detailed circuit of a preferred form of the voltage

comparator 31 and a fragmental portion of the restorer 37, an electric discharge device, such as triode 39, is fed through its control grid from the output of the pulse integrator 3. In this arrangement a coupling condenser 40 is employed to couple the control grid to the integrator 30. This grid is normally maintained at ground potential by the grid resistor 41, while the drop across cathode resistor 42 normally biases the cathode sufficiently positive to maintain the tube in substantially cutoff condition. The anode of tube 39 is fed through load resistor 70 from voltage source 71 and is coupled through a resistor 43 and blocking condenser 80 to one end of a plurality of diodes, 44, 44, 44 which are themselves connected in series between locking condensers 45, 46. A ground return for the system is completed through the resistors 47, 81. In addition this diode circuit is coupled through condenser 45 to saw-tooth generator 33. The diode circuit feeds into a univibrator which includes a normally inoperative triode 48 coupled through resistor 50 and condenser 51 to normally operative triode 49. The control grid of triode 48 is maintained at substantially ground potential by input resistor 52, and the cathodes of triodes 48, 49 are joined together and coupled to ground through a common cathode resistor 53. This univibrator circuit is similar to that disclosed and used in the system of my prior copending application, supra, where its operation is fully described.

The output of the univibrator of comparator 31 is connected to the intensity grid of cathode ray tube 36 and controls the beam intensity of such tube since it is normally biased to cut off by any suitable source (not shown). It also feeds the restorer 37, passing through a differentiating and clipping network, including condenser 54 and resistors 55, 70, to the control grid of triode 56. The output of tube 56 feeds through line 57 to tube 74 and to tubes 58, 59, 59' of the restorer shown in detail in Fig. 10. It will be apparent that the restorer circuit is similar in most respects to the one employed in the displacement analyzer form of system heretofore described in connection with Fig. 4.

In its operation, a pulse at point A', indicated by curve A' of Fig. 7, is fed to integrator 30 causing it to impress a wave such as is indicated by curve Z of Fig. 7 through condenser 40 upon the control grid of tube 39. In response thereto tube 39 fires or commences to conduct. This causes a negative pulse to appear at H of similar configuration to that denoted by the curve positioned adjacent that point. This action places a bias on the diodes 44, 44, 44, and such bias is maintained until overcome by the rising potential of the saw-tooth wave delivered by generator 33 at point X and indicated by curve X of Fig. 7. Thereafter a positive potential is placed upon the control grid of tube 48 so that the univibrator portion, including tubes 48, 49, of the comparator 31 delivers a square or rectangular wave, as indicated by curve W of Fig. 7, to raise the potential of the intensity grid of the tube 36 so that the beam may appear upon the screen of the cathode ray tube. It also impresses a square or rectangular wave on the restorer circuit 37 including condenser 54 and resistor 70, which differentiates it in the manner heretofore described in connection with Fig. 4, creating a clipped positive and a sharp negative pulse, and rendering tube 56 operative. Operation of tube 56 produces, in its

output circuit, a small negative pulse at the formation of the rectangular pulse and a very much larger positive pulse of substantially rectangular configuration as a result of the collapse of the rectangular pulse. The configuration of the pulse is controlled by the clipping action caused by the resistor 55 in the grid circuit of the tube. This positive pulse at the anode is then led by line 57 to tubes 58, 59, and 59' of Fig. 10 to overcome their negative bias and render them operative for the purpose indicated hereinafter. It is also fed through condenser 71 to the input circuit of tube 74 which is normally biased to cutoff by source 73 acting through resistor 72. By overcoming the bias the tube 74 is rendered conductive and provides a discharge path to ground through lead 15 for the control condenser of pulse integrator 30, rendering the tube therein inoperative, as heretofore described in connection with the circuits of Fig. 4. This restores pulse integrator 30 for the next pulse.

Referring now to the L. C. circuit of Fig. 10, it will be noted that line 57 from the first tube of the restorer circuit 37, referred to above, feeds the triodes 58, 59, and 59' also of the restorer circuit, through blocking condensers 60, 61, and 61'. Triodes 58, 59, and 59' are preferably negatively biased to a point at or near cutoff by E. M. F. sources 62, 63, and 63', respectively, coupled through resistors 64, 65, and 65'. The L. C. circuit 35 consists essentially of a condenser 66 and an inductance 67 connected by leads 68, 69 and a ground connection across the horizontal and vertical plates, respectively, of the cathode ray tube 36. The anode circuits of triodes 58, 59 and the cathode circuit of tube 59' are then connected to the leads from the condenser 66 and inductance 67 of the L. C. circuit to control their operation by bringing them to substantially ground potential during periods of operation of tubes 58 and 59 or 59'. Since the anode of tube 59 and the cathode of tube 59' are tied to the inductance 67, it will be noted that tube 59 can operate only over the time interval represented by the positive portion of the voltage characteristic curve L of the Fig. 7, and that tube 59' will operate over the time interval represented by the negative portion of that curve.

When a pulse, delayed by line or network 32 of Fig. 6 reaches the input of univibrator 34, it produces a rectangular or square pulse in the output thereof, and its relation to other pulses and waves of the system is indicated by curve V of Fig. 7. This wave is impressed upon the L. C. circuit 35. As a result the entire voltage of the impressed wave appears across the inductance 67 at the moment of rise of the impressed wave. The voltage on inductance 67 will become less according to the well-established cosine law and the voltage on condenser 66 will build up according to the well-established sine law. The relationships of these voltages are indicated at L and C of Fig. 7. These are also the voltages appearing on the vertical and horizontal deflecting plates of the cathode ray tube 36 and give a comparison with the other waves or voltages at various points in the system. At the point where voltage comparator 31 acts to remove the voltage on the intensity grid of cathode ray tube 36, it also acts on the restorer circuit 37 to cutoff tube 56, which permits tubes 58, and 59 or 59' to return to the operative condition. This is accomplished by the collapse of the substantially rectangular positive wave appearing at the output of tube 56 as a result of the cessation of

signal from the comparator 31. The collapse of the square wave from comparator 31 was differentiated by condenser 54 to provide a negative pulse on the control grid of tube 56 of Fig. 9 and cause it to become less conducting. This produced a substantially rectangular positive wave on the output of tube 56 which overcame the bias on tubes 58, and 59 or 59', depending upon the timing thereof, and rendered them operative. The operation of tubes 58, 59 or 59' provided low impedance paths around condenser 66 and inductance 67 to ground and abruptly interrupted the voltage relation curves, as indicated at L and C of Fig. 7. However, lack of further signal from comparator 31 leaves tube 56 in a substantially nonconducting state and with the collapse of the positive wave in the output circuit of tube 56, the negative bias on tube 58 and tube 59 or 59' returns them to the nonconducting state. With the charge removed from the plates of cathode ray tube 36 and tubes 58, 59, or 59' rendered nonconducting, the system is readied for the next pulse. In this connection it will be understood that if the positive wave arrives through lead 57 at the time when the voltage across the inductance 67 is positive, as indicated by the characteristic curve L of Fig. 7, the tube 59 will conduct. However, if the positive wave arrives on lead 57 at a time when the voltage across inductance 67 is negative, as indicated by the characteristic curve, then tube 59' alone will operate.

In connection with the system of Fig. 3 it may be noted that the conventional driving amplifiers for the cathode ray tube have been omitted. This was done for the sake of simplicity.

While the heater elements for the various tubes and the power supply has not been included herein, it will be understood that they are of conventional form and were only omitted for the purpose of clarity in disclosing the more important details of the invention. In addition, applicant has indicated the restoring circuit for the pulse integrator 30 as a part of the general restorer circuit 37, but it will be understood that an entirely separate restorer, such as disclosed at 9 of Fig. 4, may be employed, and that it may be fed from point W of Fig. 6.

Having thus described my invention, I claim:

1. A system for determining the magnitude distribution of a series of events comprising a translator for converting the events into electronic pulses, a pulse integrator fed by the translator for producing and sustaining a signal corresponding to the magnitude of each of said pulses, an indicator for reproducing the signals from the integrator, and means responsive to said pulses for controlling the operation of the indicator and for restoring the integrator.

2. A system for determining the magnitude distribution of a series of events comprising a translator for converting the events into electronic pulses, a pulse integrator fed by the translator for producing and sustaining signals corresponding to the peaks of said pulses, a cathode ray discharge device having a screen, said discharge device being fed by said integrator to reproduce the signals on its screen and a control circuit responsive to said pulses for restoring the integrator and for controlling the display of said signals on said screen.

3. A system for determining the magnitude distribution of a series of events comprising a translator for converting the events into elec-

tronic pulses, a pulse integrator fed by the translator for producing and sustaining signals corresponding to the magnitude of said pulses, a cathode ray discharge device having a screen for reproducing said signals, and a control circuit including a delay circuit responsive to said pulses for activating said discharge device to display the signals and for restoring said integrator to inoperative position.
